CENTRIFUGAL WASHING CONTROL

Ernest G. Kochli, Brooklyn, N. Y., assignor to
Applied Sugar Laboratories, Inc., New York,
N. Y., a corporation of New York

Application May 22, 1939, Serial No. 274,928

9 Claims. (Cl. 210—67)

This invention relates to improvements in the washing or affination of sugar.

In the refining of sugar the raw sugar is commonly mixed with an impure syrup known as "green syrup" to make a mixture or magma capable of transportation as a liquid. The latter is then sent to centrifugals where it is first subjected to centrifugal action to separate the green syrup. Thereafter the residual sugar is washed with water to remove as much adhering green syrup or molasses as may be removed by this means.

For the best results there is a critical point where the wash water should be applied. If it is applied too soon the affination syrup will be contaminated with green syrup. If too late, time is lost.

Numerous efforts have been made to automatically apply the wash water at just the right moment, none of which have been entirely satisfactory.

I have discovered means whereby the wash water can be applied automatically at any predetermined speed of the basket or centrifugal, preferably at the moment that the centrifugal has attained a speed at which the maximum amount of green syrup has been extracted. This speed varies, in the same centrifugal, with different sugar and in a typical case may be between 90 and 100 per cent of maximum speed.

The following are some of the objects of the invention:

1. To correlate the speed of the centrifugal with the application of wash water.
2. To provide means for automatically applying wash water at any predetermined speed of the centrifugal.
3. To apply the wash water during an accurately controlled time interval.
4. To automatically direct the respective effluents, i. e., green syrup and affination syrup, into different channels.

In accordance with the invention, the centrifugal is provided with a speed responsive means and this is used to set in motion mechanism which accomplishes the objects above set forth. For example, assume that the centrifugal is driven by an electric motor. It has been found that when the current is first applied it is very high, relatively, that it then decreases and finally reaches a stable minimum. Correspondingly the basket speed is low at first. It then increases and finally reaches a stable maximum. If the values for current and basket speed are plotted against time, it will be found that the maximum basket

speed and minimum current are attained at the same time and that for every basket speed there is a corresponding current value; and by employing an appropriate current responsive means in cooperation with other mechanism, I am enabled to apply wash water at any given current value and therefore at any desired basket speed. I am not however limited to the relationship between basket speed and current value, as I may employ other speed responsive means to produce the above objects, as hereinafter more fully set forth.

In the accompanying drawings—

Fig. 1 shows in perspective and diagrammatic form an assembly of apparatus suitable for the practice of the invention and

Fig. 2 shows the corresponding wiring diagram. Fig. 3 shows a form of speed responsive device different from that shown in Fig. 2.

Like parts are designated by like numerals.

20 The motor 1 drives centrifugal 2. Current is supplied by power circuit 3B controlled by magnetic switch 5, through remote control switch 3 and time clock mechanism 4. When remote control switch 3 is in "off" position, the coils 5A and 25 the coil 6A of solenoid 6 are deenergized and plunger 6B depresses lock-out arm 7, keeping relay contacts 9 open. Coil 8A of solenoid 8 is energized by transformer 10 in series with the power circuit which feeds the motor 1.

30 Plunger 8B moves up and down with variations in the current in the power circuit and in coils 10 and 8A. The valve seat 12A (see Fig. 2) is normally held closed by gravity or a spring acting upon plunger 12C and is opened by the retraction 35 of plunger 12C when coil 12B of the solenoid 12 is energized. The period during which valve 12A is held open is governed by timing mechanism 13. When the valve 12A is open water is delivered to the centrifugal through spray 14. Coil 19

40 solenoid 20 operates plunger 20A, which in turn opens and closes contacts 21. Coil 28 in relay or solenoid 29 is energized simultaneously with coil 19 and coil 28 operates plunger 30 which is adjustably time-retarded by suitable mechanism, 45 such as dash-pot 30A. Plunger 30 serves to open and close contacts 31. Coil 36 of relay 37 operates plunger 36A which serves to open and close contacts 38.

Solenoid 20 and timing mechanism 13 controls 50 the operation of valve 12A. Relays 29 and 37 control the operation of valve 32, which will be presently described.

Hopper 40 contains the mixture of sugar and green syrup for delivery to the basket 2 through gate 11. Effluent from the basket 2 is delivered

from spout 23 to the selectively-operating receiver 24. The valve 32 admits compressed air from line 32A into cylinder 33 when said valve 32 is opened. Opening occurs when the coil 32B is energized and retracts plunger 32C. Arm 34 is arranged to be forced counter-clockwise by the pressure in cylinder 33 and by means of lever 26, to rotate the selectively operating funnel 24 counter-clockwise, so as to cause effluent to be delivered into the channel 35. Valve 32 is a three way valve. In its normally closed position it not only cuts off the supply of compressed air to the chamber 33, but also establishes communication between this chamber and the atmosphere, thus permitting the arm 34 carrying a piston to be forced in a clockwise direction by the spring 25, thus causing funnel 24 to be tilted, to be reset for delivery of effluent into channel 27 at the beginning of the next cycle.

The operation begins by closing remote control switch 3. This energizes the circuit K₁K₂ and coil 5A which through plunger 5B closes the switch 3A and power circuit 3B, thus starting the motor 1 and the centrifugal 2. A transformer 10 is in series with the power circuit, the secondary of this transformer being a part of a circuit A₁A₂ including the coil 8A. The current in the circuit A₁A₂ and coil 8A is an inverse function of the speed of the motor and centrifugal and decreases as the centrifugal speed increases. The plunger 8B moves upwardly as the current in coil 8A increases and downwardly by gravity as said current decreases and can be adjusted to close contacts 9 of circuit B₁B₂ at any predetermined value of the current in the power circuit and consequently any predetermined centrifugal speed. In a typical case it is adjusted to close contacts 9 at a point between 90 and 100 per cent of maximum speed, as it is desirable to apply the wash water at this point with numerous kinds of sugars. The plunger 8B is free to move because plunger 6B has been retracted by coil 6A energized by coil 5A, thus putting the lock-out arm 7 in inoperative position.

The transformer 10 is an illustration of a speed-responsive means and serves satisfactorily when the centrifugal is driven by an electric motor. Since it may be driven by other means, e. g. a belt drive from a power shaft, a quite different form of speed responsive means may be employed. This alternative form is shown by centrifugal relay 39 having an arm 39A which at a predetermined speed closes contacts 40A, by means of circuit P₁P₂, thus closing circuit B₁B₂. When the contacts 9 and circuit B₁B₂ are closed, three operations simultaneously occur.

First operation

Valve seat 12A is opened by the action of coil 12B of solenoid 12 on the valve stem 12C. Water is then admitted to the sugar in centrifugal 2 at precisely the moment when the centrifugal has attained a predetermined speed, this being the moment when the green syrup has left the basket through conduit 23.

Second operation

The time mechanism 13 is also set in motion, by circuit C₁C₂ which starts in motion the timing motor 15, in order to control the period during which the water is applied, in a manner which will be explained as follows: the circuit B₁C₂ including coil 19 is normally inoperative because broken at the contacts 18 and the plunger 20A normally closes contacts 21, being held in contact therewith by gravity. When the contacts 18 are

closed, coil 19 is energized, thus moving plunger 20A upwardly and breaking contacts 21. This breaks the circuit B₁B₂ and valve 12A closes since it is normally held closed by gravity or spring 5 action and is opened only when coil 12B is energized by circuit B₁B₂.

Contacts 18 are closed at the end of a predetermined period as follows: the shaft 15A consists of two parts which are operatively engaged 10 by the electro magnetic clutch 17A when it is operated by the coil 17, said shaft 15A being driven by timing motor 15 and serving to drive the gears 15B and 15C. Gear 15C is provided with an arm 16 which rotates clockwise against the tension of 15 a spring and upon rotation through a predetermined arc said arm 16 engages and closes contacts 18.

The coil 17 is energized by circuit B₁C₁ simultaneously with the starting of motor 15.

- 20 When contacts 18 are closed they must remain closed until the lock-out arm 7 becomes operative to break contacts 9, through breaking of the circuit K₁K₂ (by the operation of time mechanism 4). This is necessary in order to keep the coil 19 energized and thereby keep valve 12 closed. Contacts 18 will remain closed as long as clutch 17A is locked and this will remain locked as long as coil 17 is energized. Coil 17 remains energized by circuit B₁C₁ until the breaking of contacts 9. 30 When that occurs, contacts 18 are broken and time mechanism 13 is reset by the action of the spring acting on arm 16.

Third operation

- 35 Up to this time funnel 24 is in the position shown, directing green syrup into the channel 27. Mechanism is now set in motion to direct the effluent from the centrifugal 2 into the channel 35 after a time delayed interval. This mechanism comprises an actuating relay 29, a maintaining relay 31 and valve 32. The reason for these two relays is as follows: At the end of a predetermined time, the time mechanism 4 operating through the circuit K₁K₂ deenergizes coil 5A and breaks power circuit 3B. When coil 5A is de-energized, coil 6A becomes likewise deenergized, plunger 6B drops, engages lock-out arm 7 in the position shown and breaks contacts 9, thus simultaneously breaking contacts 31 because of the deenergization of coil 28. Coil 36 remains energized because of its direct connection to the remote control circuit M₁M₂ through the contacts 38 and the circuit G₁G₂ remains energized notwithstanding the breaking of contacts 9. Thus the valve 32 remains open and maintains funnel 24 in a position to direct the effluents into channel 35 after the breaking of the power circuit. The reason for desiring this is that effluent continues to flow from the centrifugal after the breaking of the power circuit and means are provided to keep this effluent directed into the channel 35. Notwithstanding the breaking of contacts 9, coil 32B will continue to be energized, thus directing effluent into channel 35 so long as coil 36 is energized and coil 36 remains energized after the circuit K₁K₂ is automatically broken by time mechanism 4 and until manually controlled switch 3 is opened.
- 60 The valve 32 remains open and maintains funnel 24 in a position to direct the effluents into channel 35 after the breaking of the power circuit. The reason for desiring this is that effluent continues to flow from the centrifugal after the breaking of the power circuit and means are provided to keep this effluent directed into the channel 35. Notwithstanding the breaking of contacts 9, coil 32B will continue to be energized, thus directing effluent into channel 35 so long as coil 36 is energized and coil 36 remains energized after the circuit K₁K₂ is automatically broken by time mechanism 4 and until manually controlled switch 3 is opened.
- 65 The operation of actuating relay 29, maintaining relay 31 and valve 32 will now be described:

When coil 28 is supplied with current by circuit D₁D₂ plunger 30 which is adjustably time-delayed by dash-pot 30A moves upwardly during a predetermined time interval and closes contacts 31, thus energizing circuit E₁E₂ containing coil

36. Plunger 36A then immediately closes circuit G₁G₂ containing coil 32B in valve mechanism 32. The plunger 32C moves upwardly opening the valve 32 and admitting compressed air from the line 32A. The arm 34 moves to the left causing lever 26 to move in a counter-clockwise direction against the tension of spring 25, thus causing funnel 24 to tilt in a counter-clockwise direction and direct the effluent into channel 35. Thus, for an adjustably predetermined short interval after the application of spray water from spray 14, the effluent passes into the green syrup channel 27. The first washings contain substantially all the green syrup not removed by centrifugal action and by the operation and mechanism described. Such residual green syrup on the sugar crystals does not contaminate the subsequent af-

fination syrup which flows through channel 35. Upon breaking or opening of manually controlled remote control switch 3, coils 36 and 32B are deenergized, thus permitting spring 25 to reset the funnel 24 for the next cycle.

The operation or total cycle is terminated by opening remote control switch 3.

The switch 22 is provided in order to permit the application of a manually controlled washing operation independently of the automatic system. By pressing the contact plate 22A to engage the contacts 22B the coil 12B is segregated from the automatic system and connected directly to the remote control circuit M₁M₂.

I claim:

1. In centrifugal apparatus adapted for the purification of sugar, the combination with a centrifugal and driving means therefor; of means actuated by an operative electrical circuit to supply wash water to sugar in said centrifugal; means responsive to variations in the speed of said centrifugal; and means operated by said speed-responsive means, to place said electrical circuit in operation and thereby supply wash water at a predetermined speed of said centrifugal; and means to place said electrical circuit in inoperative condition and thereby to discontinue the supply of said wash water at the expiration of a predetermined period.

2. In centrifugal apparatus adapted for the purification of sugar, the combination with a centrifugal and driving means therefor, of supply means for delivering wash water to the sugar in said centrifugal, control means to render said supply means operative, timing means to render said supply means inoperative after a predetermined time interval; two discharge channels for conveying the effluent, effluent-receiving means selectively operable to direct the effluent from the centrifugal into either of the said two channels, timing means operable after a predetermined time interval to control said effluent-receiving means to divert the effluent from one of said channels to the other, an electrical circuit for initiating operation of said control means and said timing means, means actuated by said centrifugal at a predetermined speed of the centrifugal to control electric flow in said circuit to initiate operation of said control means and both of said timing means.

3. In centrifugal apparatus adapted for the purification of sugar, the combination with a centrifugal and driving means therefor; of means including a valve to supply wash water to the sugar in said centrifugal; means responsive solely to variations in the speed of said centrifugal; means operated directly by said speed responsive means to open said valve at a predetermined

speed of said centrifugal and means to close said valve after a predetermined period of time.

4. In centrifugal apparatus adapted for the purification of sugar, the combination with a centrifugal and driving means therefor; of means including a valve to supply wash water to the sugar in said centrifugal; means responsive solely to variations in the speed of said centrifugal; and means operated directly by said speed responsive means to open said valve at a predetermined speed of said centrifugal and to close said valve at the expiration of a predetermined time interval after the opening of said valve.

5. In centrifugal apparatus adapted for the purification of sugar, the combination with a centrifugal and driving means therefor, of supply means for delivering wash water to the sugar in said centrifugal, control means to render said supply means operative, timing means to render said supply means inoperative after a predetermined time interval, an electrical circuit for initiating operation of said control means and said timing means, and means actuated by said centrifugal at a predetermined speed of the centrifugal to control electric flow in said circuit to initiate operation of said control means and said timing means.

6. In centrifugal apparatus adapted for the purification of sugar, the combination with a centrifugal and driving means therefor; of means including a valve to supply wash water to the sugar in said centrifugal; means responsive solely to variations in the speed of said centrifugal; a first electrical circuit adapted upon the closing thereof to open said valve; a second electrical circuit and means adapted upon the closing thereof to break said first circuit and close said valve; a third electrical circuit adapted to be closed simultaneously with the closing of said first circuit and means operated by the closing of said third circuit to close said second circuit after the expiration of a predetermined time interval; and means operated directly by said speed responsive means to close said first electrical circuit at a predetermined speed of said centrifugal.

7. In centrifugal apparatus, a centrifuge adapted for the separation of liquid from solid material; means including a valve to supply washing liquid to the contents of said centrifugal; means responsive solely to variations in the speed of said centrifugal; means operated directly by said speed responsive means to open said valve at a predetermined speed of said centrifugal and means to close said valve after a predetermined period of time.

8. In centrifugal apparatus, a centrifuge adapted for the separation of liquid from solid material; an alternating current motor to drive said centrifugal; a power circuit supplying alternating current to said motor which current during operation varies in response to variations in the speed of said centrifugal; a transformer having its primary coil in said power circuit; a valve to supply wash liquid to the contents of said centrifugal; inductive means including the secondary coil of said transformer to open said valve at a predetermined value of the current in said primary coil and therefore at a predetermined speed of said centrifugal and means to close said valve after a predetermined period of time.

9. In centrifugal apparatus a centrifuge adapted for the separation of liquid from solid material and the washing of said solid material from which said liquid has been removed, means to drive said centrifuge; a valve to supply wash

ing liquid to the contents of said centrifuge; effluent-receiving means to receive the effluent from said centrifuge and selectively discharge said effluent to different channels; means including a first relay adapted when actuated to open said valve; means responsive to the speed of said centrifuge to actuate said relay and open said valve at a predetermined minimum speed of said centrifuge; means including an electrical relay and a time-controlled electric circuit operative 10

upon and during the actuation of said first relay to direct the effluent into a predetermined channel at a predetermined time and to close said valve upon the expiration of a predetermined time, and means to maintain said effluent-receiving means in a position to discharge the effluent into said predetermined channel at speeds of said centrifugal below said minimum speed.

ERNEST G. KOCHLI.
